* cited by examiner

Primary Examiner — Sandra Snapp(74) *Attorney, Agent, or Firm* — Fredrikson & Byron, P.A.(57) **CLAIM**

We claim the ornamental design for a seating layout for a transport vehicle, as shown and described.

DESCRIPTION

FIG. 1 is a top perspective of our new design for a seating layout for a transport vehicle;

FIG. 2 is a top view thereof;

FIG. 3 is a bottom view thereof;

FIG. 4 is a front view thereof;

FIG. 5 is a rear view thereof;

FIG. 6 is a side view thereof; and,

FIG. 7 is an opposite side view thereof.

The broken lines form no part of the claimed design.
